Patented June 1, 1920.

FIG. 1

FIG. 2

INVENTOR.

Felix Wisniewski.

BY George C. Henrick

ATTORNEY.

UNITED STATES PATENT OFFICE.

FELIX WISNIEWSKI, OF SOUTH AMBOY, NEW JERSEY.

RAIL-CLAMP.

1,342,078.

Specification of Letters Patent. Patented June 1, 1920.

Application filed October 22, 1919. Serial No. 332,468.

To all whom it may concern:

Be it known that I, FELIX WISNIEWSKI, a citizen of Poland, residing at South Amboy, county of Middlesex, and State of New Jersey, have invented certain new and useful 5 Improvements in Rail-Clamps, of which the following is a specification.

This invention relates to improvements in rail clamps, particularly clamps operated 10 by the actuation of a clamping wedge.

It is the principal object of the invention to provide a rail clamp assuring a ready and effective operation as well as presenting a simple improved construction.

15 With these and other objects in view the invention resides in the novel construction, combination and arrangement of parts to be hereinafter specifically described and then claimed.

20 In the accompanying drawings:

Figure 1 is a top plan view of the rail clamp, and

Fig. 2 is a vertical cross-section of a rail with the clamp constructed according to the 25 present invention in end view.

The rail 10 is clamped onto a tie 11 by two clamp bars 12, 12 engaging the upper faces of the foot flanges of the rail upon opposite sides of the web.

30 At both sides of the rail 10 blocks 13, 13 are secured to the tie 11 by means of screw bolts 14, 14 or the like. The blocks 13, 13 are provided with recesses 15, 15 and the upper parts are cut away as at 16, 16; these 35 cut away parts being directed at both sides of the rail in opposite directions as clearly shown in the drawing. Wedges 17, 17 are movably arranged within the recesses 15, 15 so that the wider ends of said wedges will

40 point in opposite directions on both sides of the rail. These wedges press the clamp bars 12 upon the rail flange. A cross bar 18 is slidably arranged near the smaller end of each wedge and adapted to slide along the 45

cut away portions 16, 16 and is normally pressed outwardly by means of coiled springs 19, 19 wound around pins 20, 20 resting with their inner ends against the blocks 13, 13. The outward movement of the bars 18, 18 50

under the action of the springs 19, 19 is limited by a stop pin 21 in the smaller ends of the wedges upon the outside of the bars 18, 18 against which the outer edges of said bars bear.

55 The larger ends of the wedges are wider

than the recess, and it is clear that under the action of the springs 19, 19 the wedges will be drawn into the recesses 15, 15 as far as their larger ends will permit, thus insuring a positive clamping action of the clamp 60 bars upon the rails.

If it is desired to loosen the rail clamp, the bars 18, 18 are pressed back against the tension of the springs 19, 19, the retaining pins 21 are removed and the wedges can then 65 be removed from the recesses 15, 15 allowing a ready removal of the clamp bars 12.

What I claim is:

1. A rail clamp of the character described comprising in combination with a rail, cut-away blocks adapted to be secured to the ties at both sides of said rail, clamp rods in said blocks adapted to press upon the foot flanges of a rail, means in said blocks for clamping said rods against the foot flanges 75 of said rail, means for normally locking said clamping means in its operative position, and means for releasing said locking means.

2. A rail clamp of the character described, 80 comprising in combination with a rail and its foot flange, cut-away and recessed blocks adapted to be secured to the ties at both sides of said rail with the cut-away portions pointing in opposite directions, clamp rods 85 in said blocks adapted to press upon the foot flanges of said rail, wedges in the recesses of said blocks, stop pins in the smaller ends of said wedges and a spring controlled yoke for normally drawing said wedges into said 90 recesses as far as their wider parts permit.

3. In a rail clamp of the character described, recessed cut-away blocks adapted to be secured to a tie at both sides of a rail, clamp rods in said blocks, wedges in the recesses of said blocks pressing on said clamp rods and having their wider ends pointing in opposite directions on both sides of a rail, a spring controlled yoke upon the cut-away portion of said blocks, and stop pins in the 100 smaller ends of said wedges against which the movable front bars of said yoke normally rest.

4. In a rail clamp of the character described, recessed cut-away blocks at both 105 sides of a rail adapted to be secured to the tie, clamp rods in said blocks, wedges in the recesses of said blocks pointing with their smaller ends in opposite directions at both sides of a rail and pressing said clamp rods 110

against the rail foot, pins on the cut-away portions of said blocks, spiral springs wound about said pins and movable operating rods on said pins normally resting with their outer edges against stop pins in said wedges for locking said clamp rods against the rail foot, the larger portions of said wedges engaging

the recesses in said blocks, said operating rod adapted to be pressed inwardly against the tension springs for releasing said wedges and clamping rods.

In testimony whereof I have affixed my signature.

FELIX WISNIEWSKI.
